COATING MACHINE

Charles F. Schaefer, Stratford, Conn.

Application March 30, 1954, Serial No. 419,827

15 Claims. (Cl. 118—259)

The present invention relates generally to coating machines, and more particularly is directed to a machine for applying coating solutions containing volatile solvents, such as, for example, rubber cement, lacquer, paint and the like, to sheet materials.

In working with such coating solutions, the latter must be stored in a closed tank or reservoir in order to prevent the rapid evaporation of the volatile solvent since, after exposure to the atmosphere has caused solvent evaporation, many of such solutions cannot be returned or restored to their original consistency by the addition of fresh solvent. The requirement of a closed tank or reservoir presents difficulties in coating machines of the type wherein the coating is applied to the sheet materials by a coating roller. While it has been previously proposed to provide a roller coating machine with a closed tank or reservoir so as to adapt such a machine for work with coating solutions, containing volatile solvents, all of such existing machines are complex in construction and difficult to disassemble when it becomes necessary to clean the rollers and the tank or reservoir.

Accordingly, it is an object of the present invention to provide a roller coating machine which is adapted for coating sheet materials with solutions containing volatile solvents, and wherein all of the parts of the machine can be easily assembled and disassembled without requiring the use of any tools, thereby to facilitate cleaning of the machine which is frequently necessary by reason of the rapid solvent evaporation and thickening tendencies of the coating solution.

A further object of the invention is to provide a roller coating machine of the described character wherein the coating solution is contained in a closed tank or reservoir, with a continuous supply of the coating solution being pumped or conveyed from the tank to the coating roller for transfer by the latter to the sheet materials, and with the excess of the pumped solution which has been exposed to the atmosphere and to roller agitation being returned to the tank, for mixture with the main body of the solution thereby providing a continuous circulation of the coating solution to prevent excessive thickening of the latter during operation of the machine.

In accordance with the invention, the above, and other objects, features and advantages thereof, appearing in the following detailed description of an illustrative embodiment, are achieved by providing a coating machine which comprises a permanent base or frame carrying the drive mechanisms and feed rollers for cooperation with the coating roller, a tank or reservoir for the coating solution which is removably mounted on the base, a pump housing fitting loosely into the bottom of the tank and accommodating a rotatable pumping screw which acts to continuously propel coating solution from the tank into an inlet of the pump housing and through the latter for discharge at an upwardly opening outlet, a funnel member removably seating in the pump housing outlet and extending upwardly from the latter within the

2

tank, and a removable coating roller assembly which is removably mounted, as a unit, upon the top of the tank and includes a coating roller positioned above the funnel to receive the coating solution from the latter and a scraping or doctor blade for removing the excess coating solution from the coating roller with an arrangement being provided, as a part of the coating roller assembly, for adjusting the scraping blade so as to vary the thickness of the layer of coating solution applied by the coating roller to the strip or sheet materials.

It is a feature of coating machines embodying the invention that the various assemblies and parts thereof, referred to above, may be assembled and disassembled without requiring the use of any tools and the like, with the coating roller and the pumping screw being automatically coupled to the related driving mechanisms on the permanent base or frame when the coating roller assembly and the pumping screw are disposed in their respective operative positions. A further feature of the invention resides in the provision of bearings for the coating roller and for the drive of the pumping screw which effectively prevent the pumping or leakage of coating solution through such bearings thereby to avoid fouling or clogging of the several bearings.

In order that the invention may be fully and clearly understood, an illustrative embodiment thereof is herein-after described in detail and shown in the accompanying drawings, which form a part hereof, and wherein:

Fig. 1 is a vertical sectional view taken along the line 1—1 of Fig. 2;

Fig. 2 is a transverse sectional view taken along the line 2—2 of Fig. 1;

Fig. 3 is a top plan view of the coating machine of Figs. 1 and 2, but with the covers for the tank or reservoir being removed and with portions of the feed rollers being broken away to better expose the underlying portions of the machine embodying this invention;

Fig. 4 is a fragmentary top plan view of a portion of the coating machine shown in Fig. 3, but with the coating roller assembly removed, and with a part of the machine being broken away to expose the structure disposed therebelow; and

Fig. 5 is a detailed, side elevational view, on an enlarged scale of an arrangement for adjusting the scraping or doctor blade included in the coating roller assembly of the illustrated embodiment of the invention.

Referring to the drawings in detail, and initially to Figs. 1, 2 and 3 thereof, a coating machine embodying the present invention is there illustrated and generally identified by the reference numeral 10. Coating machine 10 includes a permanent base or platform 12 having an upstanding, longitudinally extending frame member 14 thereon.

A tank or reservoir for the coating solution generally identified by the reference numeral 16 is disposed on base 12 at one side of frame 14 and includes side walls 18 and 20 which, at their lower edges, seat upon base 12 and may be removably secured to the latter, a front wall 22 and a bottom wall 24 inclined downwardly toward the front to a laterally extending well or depression 26. Tank 16 further includes a back wall 28 having a rearward extension or projection 30 therein to define a filling spout communicating with the main body of the tank. If desired, an outlet 21 having a suitable removable closure thereon may be provided in one of the tank side walls adjacent the bottom thereof to permit draining of the contents of the tank 16.

In accordance with the present invention, a pump housing 32 fits freely from above into the well or depression 26 of the tank and is formed with a laterally extending bore 34 to accommodate a pumping screw which is gen-

erally identified by the reference numeral 36. Housing 32 is provided with a bearing 38 at the end of bore 34 closest to side wall 20 of the tank for rotatably supporting a shaft 40 of the pumping screw, and the pumping screw 36 further includes a helical screw or thread 42 extending around shaft 40 (Fig. 2) and into bore 34 of the pumping housing for propelling coating solution from the well 26 of the tank into the bore 34 which constitutes the inlet to the pump housing.

Pump housing 32 is further provided with an outlet 44 opening upwardly from the bore 34 (Fig. 4) and having a flaring upper portion. A funnel member 46 has the back and sides thereof converging downwardly to a spout 48 which is integral with the remainder of the funnel member and dimensioned to seat in the flaring upper portion of pump housing outlet 44. Funnel member 46 is dimensioned, as seen in Fig. 4, to fit closely between side walls 18 and 20 of the tank or reservoir 16 so that, when the spout 48 of the funnel member is engaged in the outlet of the pump housing 32, the funnel member serves to position the pump housing laterally within the well or depression 26 of the tank or reservoir. Further, the engagement of the pump housing 32 in well 26 positions the funnel member 46, in the longitudinal direction, so that the front wall of the funnel member is disposed against the front wall 22 of the tank or reservoir, as shown in Figs. 1 and 4.

Coating machine 10, in accordance with the present invention, further includes a coating roller assembly which is generally identified by the reference numeral 50. Assembly 50 is made up of two parallel side members 52 having a pair of spaced apart cross-rods 54 extending therebetween. The ends of cross-rods 54 are secured to the side members 52 by adjustable securing members or screws 56 so that the side members can be drawn toward each other by tightening of the screws 56. The side members 52 are removably secured on top of tank side walls 18 and 20 by suitable thumb screws 58 which can be manually tightened or removed without requiring the use of tools for that purpose. A coating roller 60 is mounted upon a shaft 62 having its opposite ends journaled in non-rotatable bearing housings 64 extending inwardly from side members 52 and telescoping over the related end portions of shaft 62. As seen in Fig. 2, each of the bearings 64 is sealed or packed with a material 65 capable of resisting the solvents employed in the coating solutions, for example, a packing material of the kind known as "teflon," so that when the side members 52 are drawn together, by tightening of the screws 56, the packings in bearing housings 64 are tightened against the shaft 62 and against the adjacent ends of coating rollers 60 so that entry of the coating solution into the bearings is thereby avoided.

The coating roller assembly 50 further includes a shaft 66 (Figs. 1 and 3) extending laterally between side members 52 at a location in back of the coating roller 60, with the shaft 66 supporting a scraping or doctor blade 68 for contact with the surface of coating roller 60. It is apparent from Fig. 1 that rocking or angular displacement of shaft 66 will vary the contact between blade 68 and the surface of roller 60 thereby to control the thickness of the layer of coating solution on the coating roller for transfer to the sheet materials being coated. In accordance with the present invention, such adjustable angular displacement of shaft 66 is effected by an arrangement forming a part of the coating roller assembly 50 and removable with the latter, as a unit, from the operative position upon tank 16.

In the illustrated embodiment of the invention, angular adjustment of shaft 66 is effected by an arm 70 (Fig. 5) fixed to an end of the shaft 66 at the outside of the adjacent side member 52, with the arm 70 having a longitudinally opening slot or recess 72 at its free end to receive an eccentric cam 74 mounted on a rotatable stub shaft 76 which is rotatably carried by the side member 52 and manipulated by a control knob or dial 78 (shown

in broken lines on Fig. 5). Thus, manipulation of the knob or dial 78 serves to angularly displace arm 70, through the action of cam 74, thereby to correspondingly displace blade 68 relative to the surface of coating roller 60.

Preferably, when coating roller assembly 50 is mounted upon tank side walls 18 and 20, bearing housings 64 engage in suitable arcuate recesses 80 (Fig. 4) formed in the upper edges of the sides of funnel member 46 thereby to positively position the top of the funnel member in the tank, with the surface of the coating roller 60 passing close to the upper edge of the front wall of the funnel member and the doctor blade 68 and its supporting structure substantially closing the top of the funnel member in back of the coating roller. In order to complete the closing of the top of tank 16, a removable top wall 82 (Fig. 1) extends between side walls 18 and 20 from the rear wall 28 to the shaft 66 supporting the doctor blade. Further, a swingable closure 84 covers the open top of the rearward extension 30 defining the filling spout of the tank or reservoir. As seen in Figs. 3 and 4, the opposite end portions of the upper edge of the rear wall of funnel member 46 are cut down or recessed, as at 86, to define weirs over which the excess of coating material spills for return to the main body of the coating solution in the tank 16.

As seen in Fig. 2, the mechanisms for driving pumping screw 36 and coating roller 62 include separable couplings which permit the removal of the coating roller assembly 50 and of the pumping screw from their operative positions on and in said tank 16, respectively.

The driving mechanism for pumping screw 36 includes a drive shaft 88 which is in axial alignment with the shaft 40 of the pumping screw when the latter is in its operative position and which extends through side wall 18 of the tank. Shaft 88 is permanently and rotatably journaled in a bearing housing 90 secured to or integral with the adjacent side wall of the tank and packed with a material 91 resisting attack by the solvents of the coating solutions, such as, for example, the material known as "teflon." The packing of the bearing housing 90 prevents the leakage of coating solution through the bearing to interfere with proper rotation of drive shaft 88. The end of drive shaft 88 within tank 16 and the adjacent end of shaft 40 of the pumping screw have cooperating and separable coupling elements 92 and 94 thereon to transmit the rotation of shaft 88 to shaft 40. Preferably, as seen in Fig. 2, coupling elements 92 and 94 are of the "open dog" type, that is, one of the elements has a diametrically extending rib on the end face thereof, while the other of the elements has a diametrically extending groove in its end face to receive the rib. It is apparent that, when the meshing groove and rib of the coupling elements 92 and 94 are disposed vertically, such coupling elements can be separated by lifting of the pump housing 32 with the pumping screw 36 out of well 26 at the bottom of the tank. The outer end of drive shaft 88 also carries a coupling element 96 which separably engages a complementary coupling element 98 carried by the adjacent end of a shaft 100 journaled in a suitable bearing on the permanent or fixed frame 14. Preferably, the coupling elements 96 and 98 are also of the "open dog" type so that such coupling elements can be easily disengaged to permit removal of tank 16 from base 12.

Coating roller 60 and its shaft 62 are driven by a shaft 102 (Fig. 2) rotatably supported in frame 14 in axial alignment with shaft 62 and coupled to the latter by separable elements 104 and 106 secured to the adjacent ends of the shafts 62 and 102, respectively. Preferably, the coupling elements 104 and 106 are also of the "open dog" type so that, when the meshing rib and groove thereof are disposed vertically, the coating roller assembly 50 can be lifted from its operative position upon the tank 16.

The illustrated coating machine further includes a feed roller assembly, generally identified by the reference nu-

meral 108, comprising two parallel feed rollers 110 and 112 which are rotatably supported with their axes extending parallel to that of the coating roller 60 to bear downwardly on sheet material fed between the rollers 110 and 112 and the roller 60. The feed rollers 110 and 112 are supported at one end in a head 114 mounted at the front end of a swingable support arm 116, the other or rear end of support arm 116 being secured in a bracket 118 which is carried by a support 120 swingably mounted in frame 14. Thus, arm 116 can be angularly displaced, with respect to frame 14, to vary the contact between feed rollers 110 and 112 and coating roller 60. In order to adjust the contact between the feed rollers and the coating roller, an adjustment screw 122 extends threadably through arm 116 to bear at its lower end against an abutment 124 projecting laterally from frame 14. A lock nut 126 is preferably provided on adjustment screw 122 to maintain the latter in its adjusted position. If desired, a suitable spring (not shown), can be provided between the head 114 and the frame 14 to urge the head 20 downwardly, and thereby to augment the force due to gravity in urging the feed rollers against the coating roller. It is apparent that, when the coating roller assembly 50 is to be removed from tank 16, support arm 116 can be swung upwardly about the support 120 thereby to place the feed rollers 110 and 112 in positions remote from coating roller 60 and the other removable parts of the machine.

Rotation of the feed rollers and of the shafts 100 and 102, which respectively drive the pumping screw and coating roller, is effected by a suitable gear transmission from a main shaft 128 (Fig. 3). This main drive shaft is connected to a source of motive power (not shown), such as, an electric motor mounted upon the base 12 at the side of frame 14 remote from tank 16. Main drive shaft 128 is journaled in a suitable bearing 130 carried by the frame, and a spur gear 132 is fixed on shaft 128 to mesh with a relatively large spur gear 134 which is also rotatably mounted on the frame 14. A stub shaft 136 is rotatably carried by the head 114 with its axis disposed above and between the axes of rotation of feed rollers 110 and 112. Stub shaft 136 projects from head 114 in the direction opposite to the feed rollers and carries two spur gears 138 and 140 which respectively mesh with the gear 134 and with spur gears 142 and 144 fixed to the shafts of the feed rollers 110 and 112, whereby the feed rollers are rotated in the same direction. Shaft 102, is also driven from gear 134 through a spur gear 146 (Fig. 2) fixed on shaft 102 and meshing directly with gear 134. Finally, sprockets 148 and 150 are fixed on shafts 100 and 102, respectively, and an endless chain 152 extends around such sprockets to transmit the rotation of shaft 102 to shaft 100 for effecting rotation of the pumping screw 36.

From the foregoing, it is apparent that, with the several parts of the coating machine in their operative positions, as illustrated in the drawings, pumping screw 36 propels the coating solution from the well 26 of tank 16 through the pump housing 32 and upwardly through funnel member 46 for contact with the rotated coating roller 60. Preferably, pumping screw 36 is effective to propel the coating solution through housing 32 at a rate which is substantially greater than that at which the coating roller deposits the solution upon the undersurfaces of sheet materials fed between the feed rollers 110 and 112 and the coating roller 60, so that the excess of pumped coating solution spills over the cut-out weirs 86 at the back edge of the funnel member and is returned to the main body of coating solution in the tank. Further, the thickness of the layer of coating solution applied to the sheet materials by coating roller 60 is regulated or controlled by the doctor blade 68, which returns the removed coating solution from the coating roller to the main body of the coating solution over the weirs 86. Since the top of the tank 26 is substantially closed by the coating roller 60, the doctor blade 68, and the closures 82 and 84, the

evaporation of the highly volatile solvents contained in the coating solutions is retarded, and thickening of the coating solution, during operation of the machine, is further deterred by the continuous circulation of the coating solution in the manner described above.

However, even with the above features of the described machine for resisting thickening of the coating solution, it is necessary at frequent intervals to thoroughly clean the various parts of the machine contacted by the coating solution. With a machine embodying the present invention, such cleaning of the parts contacted by the coating solution is facilitated in that the several parts can be easily disassembled without requiring the use of any tools for that purpose, to permit the immersion of the disassembled parts in a suitable cleanser or solvent.

In disassembling the parts of the machine, head 114, and with it feed rollers 110 and 112, are lifted clear of coating roller 60 and of the tank 16 by swinging arm 116 about its pivotal support 120. Then, thumb screws 58, holding the side members 52 of the coating roller assembly to the tank 16, are removed so that the coating roller assembly can be lifted, as a unit, from its operative position on the tank. Removal of the coating roller assembly frees the funnel member 46 so that the latter can be lifted out of the tank, and such removal of the funnel member disengages the spout 48 of the latter from the outlet 44 of the pump housing 32. After removal of the funnel member, the pump housing 32 and pumping screw 36 can be lifted together out of the well 26 of the tank, and then the pumping screw can be axially removed from bore 34 of the pump housing. Finally, the tank 16 itself can be removed from base 12 for drainage of the contents thereof and a thorough cleaning. Thus, a coating machine embodying the present invention is peculiarly adapted for coating with solutions containing volatile solvents in that the described machine resists evaporation of the solvent, and facilitates thorough cleaning of the various parts so that the relatively rapid thickening of such coating solutions does not have the disadvantages of requiring long inoperative periods for the purpose of cleaning away the dried collections of the coating solution.

While an illustrative embodiment of the invention has been described above and shown in the drawings, merely by way of example, it is to be understood that the present invention is not limited to that precise embodiment and that various changes and modifications may be effected therein without departing from the scope or spirit of the invention as defined in the appended claims.

What is claimed is:

1. A coating machine comprising a base, a tank for coating solution removably mounted on said base and having a laterally extending well at the bottom thereof, a pump housing seating in said well and removable upwardly from the latter, said housing having an outlet at the top thereof and accommodating a pumping member operative to propel coating solution from said well through said outlet, an upwardly opening funnel member fitting removably in said tank and held against lateral displacement by the latter, said funnel member seating at its lower end in said outlet of the pump housing thereby to prevent lateral displacement of said housing in the well and so that the housing prevents longitudinal displacement of the funnel member, a coating roller, means removably supporting said roller on top of said tank in the upper end of said funnel member and resisting upward movement of the latter relative to said tank, and means for driving said roller and said pumping member so that coating solution is pumped by the latter from said tank through said housing and funnel member to said coating roller and spills over the top of said funnel member to mix with the remainder of the coating solution in said tank.
2. A coating machine comprising a base; a tank for coating solution removably mounted on said base; a coating roller assembly removably mounted, as a unit, on said

tank and including parallel side members, cross-rods extending between said side members, means securing said side members to the ends of said cross-rods and operative to draw said side members toward each other, bearing housings extending inwardly from said side members and fixed relative to the latter, a coating roller, a shaft carrying said roller and having its ends projecting from the latter into said bearing housings, and packings in said bearing housings tightened against the ends of said roller and upon the ends of said shaft by drawing together of said side members thereby to prevent penetration of coating solution into said bearing housings; and means removably disposed in said tank for supplying coating solution from the latter to the surface of said coating roller.

3. A coating machine according to claim 2; wherein said coating roller assembly further includes a scraping blade, means mounting said blade between said side members for contact with the surface of said coating roller, and means on at least one of said members operative to adjust the contact between said blade and roller.

4. A coating machine comprising a base, a tank for coating solution removably mounted on said base and having a laterally extending well at the bottom thereof, a pump housing seating in said well and removable upwardly from the latter, said housing having a laterally extending bore therein and an outlet at the top thereof communicating with said bore, a pumping screw extending axially into said bore to propel coating solution from said well into said bore and thence through said outlet, an upwardly opening funnel member fitting removably in said tank and seating at its lower end in said outlet of the pump housing to locate the latter in said well, a coating roller, means rotatably supporting said roller and removably mounted on said tank to position said roller at the upper open end of said funnel member and to resist upward movement of the latter in said tank, and means for driving said roller and said pumping screw so that coating solution is pumped by the latter from said tank through said housing and funnel member to said coating roller and spills over the top of said funnel member to mix with the remainder of the coating solution in said tank.

5. A coating machine according to claim 4; wherein said driving means includes driving mechanism on said base, and separable transmissions between said mechanism and said roller and pumping screw to permit removal of said roller from the tank and of said pump housing and pumping screw from the well independent of said mechanism on said base.

6. A coating machine according to claim 4; wherein said driving means includes a drive transmitting shaft journaled in said tank in axial alignment with said pumping screw when the latter is operatively positioned in said well, meshing and separable couplings on the inner end of said drive transmitting shaft and the adjacent end of said pumping screw, a first drive shaft rotatably mounted on said base, meshing and separable couplings on the outer end of said drive transmitting shaft and said first drive shaft so that said tank can be removed from said base independent of said first drive shaft, a second drive positioned to be axially aligned with said coating roller when the latter is mounted on said tank, meshing and separable coupling means on said second drive shaft and connected to said coating roller to permit removal of the latter independent of said second drive shaft, and means on said base for rotating said first and second drive shafts.

7. A coating machine according to claim 6; wherein each of said meshing and separable couplings is of the open dog type to permit the separation thereof by radial displacement of the axis of one part of said coupling relative to the axis of the other part of the coupling whereby said pump housing and pumping screw can be lifted together out of said tank and said roller and said tank can be lifted off said tank and base, respectively.

8. A coating machine according to claim 4; wherein said means rotatably supporting said roller includes a pair

of side members adapted to seat on said tank, means connecting said side members, bearing means on said side members, a shaft journaled in said bearing means and carrying said coating roller, and removable means for securing said side members to the tank.

5 9. A coating machine according to claim 8; further comprising a scraping blade, means mounting said blade between said side members for contact with the surface of said coating roller, and means on one of said side members operative to vary the contact between said blade and coating roller so that said blade and roller can be removed, as a unit, with said side members and connecting means from said tank.

10 10. A coating machine according to claim 8; wherein said bearing means includes bearing housings fixed with respect to said side members and extending inwardly from the latter, and solvent impervious packings in said bearing housings; and wherein said connecting means includes means for drawing said side members toward each other thereby to press said packings around said roller carrying shaft and between said bearing housings and the adjacent ends of the coating roller for preventing penetration of the coating solution into the bearing housings.

20 11. A coating machine according to claim 4; further comprising a pair of feed rollers having their axes parallel to each other and to that of said coating roller, means supporting said feed rollers on said base for movement between an operative position contacting said coating roller from above so that sheet materials to be coated can be fed between said feed rollers and said coating roller and an inoperative position out of the path of upward removal of said tank from the base, and means on said base for driving said feed rollers.

25 12. A coating machine comprising a tank for coating solution, a coating roller mounted on top of said tank, a pump housing seating in the bottom of said tank and unattached for ready removal therefrom, a pumping member in said housing and removable with the latter, a funnel member communicating with said housing and extending upwardly to said coating roller, driving means for said roller and said pumping member, whereby the latter, when operated, continuously pumps coating solution from said tank and through said housing and funnel member to the surface of said coating roller for transfer by the latter to materials fed over the coating roller.

30 13. A coating machine comprising a tank for coating solution, a coating roller mounted on top of said tank, a pump housing seating in the bottom of said tank and unattached for ready removal therefrom, a pumping member in said housing and removable with the latter, a funnel member communicating with said housing and extending upwardly to said coating roller, driving means for said roller and said pumping member, and separable transmission means between said driving means and pumping member whereby the latter, when operated, continuously pumps coating solution from said tank and through said housing and funnel member to the surface of said coating roller for transfer by the latter to materials fed over the coating roller, said separable transmission means being adapted to permit the separation thereof whereby said housing and pumping member can be lifted out of said tank.

35 14. A coating machine comprising a tank for coating solution, a coating roller mounted adjacent the top of said tank, a pump housing seating in the bottom of said tank and unattached for ready removal therefrom, said housing having a laterally extending bore therein and an outlet at the top thereof communicating with said bore, a pumping screw lying within said bore in said housing and removable with the latter, a funnel member communicating with the outlet of said housing and extending upwardly to said coating roller, driving means for said roller and said pumping screw whereby the latter, when operated, continuously pumps coating solution from said tank

through said housing and funnel member to the surface of said coating roller for transfer by the latter to materials fed over the coating roller and spills excess solution over said funnel member to mix with the remainder of the coating solution in said tank.

15. A coating machine comprising a tank for coating solution; a coating roller assembly removably mounted, as a unit, on said tank and including parallel side members, means associated with said side members and operative to draw said side members toward each other, bearing housings extending inwardly from said side members and fixed relative to the latter, a coating roller, a shaft carrying said roller and having its end projecting from the latter into said bearing housings, packings in said bearing housings tightened against the ends of said roller and upon the ends of said shaft upon operation of

5 said means to draw together said side members and thereby to prevent penetration of coating solution into said bearing housings; and means removably disposed in said tank for supplying coating solution from the latter to the surface of said coating roller.
